SPARK PLUG

Lloyd McKinsey Field, New London, Ohio; Floyd Josephine Field Karcher, Pueblo, Colo., executrix of said Lloyd McKinsey Field, deceased, assignor, by mesne assignments, to Andrew R. Cochrane, Pittsburgh, Pa., trustee

Application May 21, 1951, Serial No. 227,330

3 Claims. (Cl. 123—169)

1

This invention relates to an improved spark plug of the general type having a valve-controlled passage which admits a fluid to the associated engine cylinder upon each intake stroke of the piston. In one example of this type of plug, the valve of the fluid admitting passage is formed by a lower positive electrode section, and to limit the inward opening movement of this valve the negative electrode is utilized as a stop. This, however, results in a severe hammering action of the valve upon the negative electrode and necessitates that the latter be of unusually rugged form.

One object of the present invention is to provide an improved construction in which the opening movements of the valve are limited by a portion of the plug insulator instead of by the negative electrode.

In attaining the above object, the upper end of the lower electrode section is provided with a valve head within a recess in the insulator and said valve head simply strikes the bottom of this recess to limit valve opening; and a further object is to provide an improved insulator which facilitates manufacture with the required recess and facilitates assembly with the valve head in said recess.

The insulator is of sectional construction with the valve-head-receiving-recess formed in one of its sections, and a further object is to so secure the insulator sections together that there will be no danger of current leakage or compression leakage between them.

Another object is to make novel provision for conducting the current to the lower electrode section from a fixed upper electrode section acting as a binding post for the spark plug wire.

Yet another object is to provide a simple yet durable construction which may be expeditiously manufactured and marketed at a reasonable price.

With the above and other objects in view that will become apparent as the nature of the invention is better understood, the same consists in the novel form, combination and arrangement of parts hereinafter more fully described, shown in the accompanying drawing, and claimed.

In the drawing:

Figure 1 is a vertical longitudinal sectional view showing one form of the improved plug. Figure 2 is a lower end view of the upper insulator section of Figure 1.

Figure 3 is an upper end view of the lower insulator section of Figure 1.

Figure 4 is a perspective view of the conductor

which extends between the upper and lower sections of the positive electrode; and

Figure 5 is a view similar to Figure 1 but partly in side elevation, showing a second form of construction.

In the drawing above briefly described, one suitable form of metal shell is shown at 6, said shell having a threaded lower end 7 for reception in one of the usual spark plug openings of the cylinder head of an internal combustion engine. The shell 6 is provided at its upper end with an insulator-retaining ring nut 8, and below this nut said shell has the customary upwardly facing shoulder 9. A negative electrode 10 is secured to the lower end of the shell 6 and projects inwardly therefrom.

The insulator shown in Figures 1, 2, and 3 comprises an upper section 11 and a lower section 12; while that shown in Figure 5 comprises an upper section 11^a, a lower section 12^a and an intermediate section 13. The upper insulator section, in each case, carries a fixed upper positive electrode section 14 having a longitudinal port 15 from end-to-end, while the lower section carries a lower reciprocable center electrode section 16; said section 16 having a valve head 17 integral with or suitably secured to its upper end. The periphery of the electrode section 16, at the lower end portion of the latter, is radially spaced from the inner end of the negative electrode 10 to provide a spark gap.

The upper insulator section 11 of Figure 1 is provided at its lower end with a head 18 received in the shell 6. In the lower end of this head 18, there is a central downwardly opening recess 19 which receives the valve head 17 of the lower electrode section 16. A central port 20 in the insulator section 11 communicates at its lower end with the recess 19, and the corner 21 at the juncture of said port and recess forms a seat for the valve head 17. The lower end of the upper electrode section 14 is suitably secured in the upper portion of the port 20.

The lower insulator section 12 of Figure 1 is provided at its upper end with a head 22 which abuts the head 18 of the upper section 11. The two heads 18 and 22 are clamped in the shell 6 between the ring nut 8 and shoulder 9, and suitable gaskets 23 provide sealed connections. The insulator section 12 is formed with a central port 24 which loosely receives the lower electrode section 16, and to prevent the head 17 of said section 16 from closing this port, the upper end of the head 22 is formed with radial grooves 25 extending from said port to the recess 19.

The abutting ends of the two heads 18 and 22 are provided with concentric tightly intermeshing ribs 26 and 27 respectively. The distance from the recess 19 to the periphery of the insulator, measured along an undulating line following the surfaces of the ribs 26 and 27, is considerably greater than the length of a straight radial line from said recess to said periphery. Thus, the distance which a leaking current or leaking compression would have to travel is materially increased by the intermeshed rib construction. Therefore, there is no danger of faulty plug and engine operation due to current or compression leakage between the heads 18 and 22, even if nothing but contact of the two ribbed heads is relied upon to effect the required seal, whereas mere contact of two flat surfaces on said heads might permit some leakage, due to the shortened path along which such leakage might travel. The construction under consideration is particularly advantageous with present day high-compression engines in which the high compression not only seeks to escape at every possible point, but in which said high compression sets up great resistance to the jumping of the spark and the high tension current will therefore take any possible course of less resistance.

To establish an electrical connection between the upper electrode section 14 and the lower section 16, at least at the moments when the plug must fire, a conductor 28 is provided in the port 20. In the present disclosure, this conductor is a zigzag length of fine wire having a horizontal coil or ring 29 at its upper end and a similar coil or ring 30 at its lower end. These rings contact with the electrode section 14 and the valve head 17 respectively, when said valve head is closed against the seat 21. This valve head, in the present disclosure, is conical with its apex portion extending into the port 20, and the ring 30 of the conductor 28 surrounds said apex portion and thus remains in proper relation with the valve head. The reciprocatory movements of the valve however are in no sense dependent upon the conductor 28, valve opening and closing being caused entirely by the minus and plus pressure in the engine cylinder, respectively.

In Figure 5, the heads 18^a and 22^a of the insulator sections 11^a and 12^a are provided with flat inner ends 26^a and 27^a, respectively. The intermediate insulator section 13 is a flat-sided ring, the sides of which abut the surfaces 26^a and 27^a, respectively. The central opening 19^a of this ring provides a recess receiving the valve head 17 of the lower electrode section 16. The insulator section 13 may be of a softer insulating material than the sections 11^a and 12^a and may thus have some yieldable compressibility, to act as a gasket and thus prevent compression and current leakage. However, a sealing cement could of course be used between the insulator sections if desired. It will also be understood upon an inspection of Figure 5 that a recess comparable with the recess 19^a illustrated, may be formed in the upper side of the head 22^a with the valve head 17 positionable therein and that the intermediate insulator section 13 of the plug may have the wall of the central opening thereof dimensioned to constitute a valve seat for engagement with the valve 17.

The grooves 25^a, seat 21^a, ports 20^a and 24^a, and conductor 28^a of Figure 5, correspond to the grooves 25, seat 21, ports 20 and 24, and conductor 28 of Figure 1.

During each intake stroke of an engine equipped with the improved plug, fluid enters the cylinder through the port 15, port 20 or 20^a, recess 19 or 19^a, grooves 25 or 25^a, and port 24 or 24^a, and this fluid performs a cooling function adding to the life of the plug. Upon each compression stroke, the lower electrode section 16 is forced upwardly and the valve head 17 seats against the seat 21 or 21^a, preventing escape of compression. Whenever the head 17 is seated, the conductor 28 or 28^a establishes an electrical connection between the upper electrode section 14 and the lower electrode section 16, providing for conduction of the high tension current to the section 16 at the proper time.

As a further means to eliminate any possible current leakage, it is also intended that the upper end lower insulator sections 11 and 12 have registering or aligned annular grooves or channels opening at the meeting ends of the insulator sections and concentric with the longitudinal axis of such sections for the reception of a mica or other insulation cuff or cylinder. It will also be observed that the shell holding the insulator is of two-piece construction whereby upon removal of the ring nut 8 all parts of the plug may be removed from the shell 6 for the replacement of any part thereof.

From the foregoing, it will be seen that novel and advantageous provision has been made for attaining the desired ends, and while preferences have been disclosed, variations may of course be made within the scope of the invention as claimed. For example, while the valve head 17 is shown of conical formation, it could well be of other configurations to accomplish the desired purpose. Further, it will be understood that the conductor 28 or 28^a may assume other shapes, its function being merely to establish a current flow path between the upper electrode section 14 and the lower central electrode section 16.

I claim:

1. A spark plug comprising a central insulator having an internal recess between its ends, said insulator having an upper fluid admission port from its upper end to said recess, said insulator also having a lower fluid conducting port from said recess to the lower end of the insulator, a lower positive electrode section reciprocable in said lower port and having a valve head at its upper end, said valve head being disposed in said recess and having limited vertical movement therein, said lower port having radial grooves leading from its upper end and terminating beyond the periphery of the valve head whereby said valve head may rest on the bottom of said recess without closing said lower port when said valve head is lowered, said valve head being shaped to close said upper port when raised, means for conducting current to said lower electrode section including an upper electrode section having a binding post, and a shell in which said insulator is mounted, said shell having a negative electrode spaced laterally from the lower end portion of said lower electrode section, said insulator being transversely divided into sections which abut each other, said recess being formed in at least one of said insulator sections, said insulator sections having tightly intermeshed ribs on their abutting surfaces.

2. A spark plug comprising a central insulator having an internal recess between its ends, said insulator having an upper fluid admission port from its upper end to said recess, said insulator also having a lower fluid conducting port from

said recess to the lower end of the insulator, a lower positive electrode section reciprocable in said lower port and having a valve head at its upper end, said valve head being disposed in said recess and having limited vertical movement therein, said lower port having radial grooves leading from its upper end and terminating beyond the periphery of the valve head whereby said valve head may rest on the bottom of said recess without closing said lower port when said valve head is lowered, said valve head being shaped to close said upper port when raised, means for conducting current to said lower electrode section including an upper electrode section having a binding post, and a shell in which said insulator is mounted, said shell having a negative electrode spaced laterally from the lower end portion of said lower electrode section, said insulator being transversely divided into sections which abut each other, said recess being formed in at least one of said insulator sections, said insulator sections having tightly intermeshed concentric ribs on their abutting surfaces.

3. A spark plug comprising a central insulator having an internal recess between its ends, said insulator having an upper fluid admission port from its upper end to said recess, said insulator also having a lower fluid conducting port from said recess to the lower end of the insulator, a lower positive electrode section reciprocable in said lower port and having a valve head at its upper end, said valve head being disposed in said recess and having limited vertical movement therein, said lower port having radial grooves
